Primary Examiner — George D Kirschbaum*Assistant Examiner* — Jennifer Watkins(74) *Attorney, Agent, or Firm* — Sperry, Zoda & Kane(57) **CLAIM**

The ornamental design for an intensity regulation exercising mat, as shown.

DESCRIPTION

FIG. 1 is a front perspective view embodying my new design;

FIG. 2 is a top elevational view thereof;

FIG. 3 is a bottom elevational view thereof;

FIG. 4 is a left side elevational view thereof;

FIG. 5 is a front plan view thereof;

FIG. 6 is a rear plan view thereof;

FIG. 7 is a perspective view of the mat shown rolled and ready for transport; and,

FIG. 8 is a front plan view of the configuration shown in FIG. 7.

The broken line showing of an intensity regulation exercising mat is for the purpose of illustrating stitching that forms part of the claimed design.
